UNITED STATES PATENT OFFICE.

CLARENCE A. FULLERTON, OF NEW YORK, N. Y.

WINDOW-FRAME.

1,268,108.

Specification of Letters Patent. Patented June 4, 1918.

Application filed March 27, 1915. Serial No. 17,510.

To all whom it may concern:

Be it known that I, CLARENCE A. FULLERTON, a citizen of the United States, residing at New York, in the county of New York and State of New York, have invented certain new and useful Improvements in Window-Frames; and I do hereby declare the following to be a full, clear, and exact description of the invention, such as will enable others skilled in the art to which it app pertains to make and use the same.

This invention relates to frame constructions for windows and the like and more particularly to the specific formation of the bars of which the frames are made.

It has for an object to provide a composite rail in which a series of lines of contact between the meeting members is formed to produce resistance against the inward passage of cold air and the like.

Further objects will be apparent from the following specification, appended claims and drawings in which:

Figure 1 is an elevation of a portion of a window,

Fig. 2 is a horizontal sectional view through a portion thereof, as on the line 2—2 of Fig. 1,

Fig. 3 is a vertical section showing the movable part of the window pivoted on a horizontal axis,

Fig. 4 is a horizontal sectional view as on the line 4—4 of Fig. 1, and

Fig. 5 is a cross sectional view of a modified form of composite rail showing the fixed and movable parts in contacting position.

In carrying out this invention, it will be evident to those skilled in the art that the interchangeable parts produce a compact and beneficial design in which the necessary contacting faces produce a weather tight joint. In the construction of a frame of this kind, it is necessary to have the parts thereof on the opposite sides of the pivot oppositely arranged and furthermore, in having the parts assembled as shown, the stationary and movable parts produce a completed section having a minimum cross sectional area.

Referring to the drawings, there is shown a portion of a window having the usual muntins 10 and transoms 11 in which the panes of glass 12 are disposed and in said window are sections 13 which may be swung on the axes 14 as in the usual construction.

In this type of construction, the frames for

the sections 13 are indicated as at 15 and are of the same general dimensions as the transoms 11.

Referring to Fig. 3 of the drawing in which the detailed construction of the frames 15 is formed, there is shown a rail 16 which is provided with the flange 17 against which the glass 12 is placed and said glass is retained by a strip 18 which may be provided across the horizontal sections with a flange 19 to form a gutter 20 for the condensation. The rail 16 is provided with flanges 21 in which the dove-tail slots 22 are formed and to one of the flanges 21 a plate 23 is attached in having a dove-tail bead 24 slidably engaging the slot 22. The foregoing construction is the equivalent of the transoms 11 and remains relatively fixed with respect to the section 13, of which the frame comprises a rail 25 which is similar to the rail 16 in having the fixed flange 26 and removable flange 27 to retain the glass 12 and the flanges 28 in which the dove-tail slots 29 are formed. One of the flanges 28 is adapted to bear against the plate 23 and the opposite flange is adapted to support a plate 30 which has a dove-tail bead 31 formed thereon to engage in the dove-tail slot 29 of the flange 28. The plate 30 has a face which is adapted to bear against one of the flanges 21. Each of the rails 16 and 25 is provided with a dove-tail slot 32 in which the dove-tail bead 33 of a bar 34 is slidable, of which one of the faces of each of these bars is beveled to present contacting faces as clearly shown. The parts of the frame to the opposite sides of the pivot 14 are assembled in reverse positions to provide clearance in the swinging of the sections 13. The rail 25 may be continuous about the frame and bars 33 and plates 30 may have slid able engagement with the rail 25 to present these bars and rails in the proper positions. The plate 30 may be provided with a latch 35 to which the cord 36 may be attached so that pulling the cord will release the latch 35 and cause the frame 13 to swing. This frame is returned to closed position by pulling the cord 37 which passes over the pulley 38 carried by the frame 39 which may be attached to the rail 23 adjacent to the bottom of the frame and said cord may be attached to the eye 40 which is attached to the lower rail 25. It is seen that the fixed and movable parts are of such a cross section that when these

two parts are brought into bearing relation, the cross sectional area is substantially rectangular having dimensions equal to the lengths of the sides of each of the sections 5 independently so a minimum of space is consumed in the construction of the frame.

Fig. 2 of the drawing shows the frame 13 removed and the relative positions of the rails, plates and bars to the opposite sides 10 of the pivot point.

Fig. 4 shows a sectional view through the adjacent edges of the frames 13 and the fixed frame therebetween, showing similar parts to those described in Fig. 3.

Fig. 5 is a slightly modified form in which the angle rails 41 and 42 have abutting faces 43 and 44 and dove-tail beads 45 and 46 formed on one of the flanges of each of the rails respectively. A bar 47 having a flange 20 48 formed thereon is slideable on the bead 45 and a bar 49 with the offset flange 50 is slideable on the bead 46.

Various modifications may be made within the scope of this invention but in each 25 instance, the association of a number of interchangeable parts having standard base members with standard attachments which may be assembled in reverse positions where desired, will be apparent and the drawings 30 are submitted for illustrative purposes only.

Having thus described this invention, I claim:

1. In a structure of the class described, a composite bar formed of continuous rails 35 maintained in spaced relation, each of said rails having flanges formed along the edges thereof to produce a channel structure in cross-section, said flanges having the outer faces thereof provided with continuous undercut slots, said rails having the adjacent 40 faces thereof provided with continuous undercut slots formed centrally therealong, side plates carried by some of said flanges along portions of the length of said rail, 45 said side plates having continuous enlarged beads formed thereon to engage in the undercut slotted portion of said flanges, said

side plates having the free edges thereof adapted to contact with the exposed faces of the flanges of the opposite rails, central 50 sealing bars carried by said rails having enlarged beads to engage in the continuous central slots formed along said rails, and said side plates and said central sealing bars being reversibly carried in the slotted portions of said rails.

2. In a structure of the class described, a bar of composite formation comprising rails maintained in spaced relation, having one of said rails movable with respect to the other, 60 flanges formed along the edges of said rails, said flanges having continuous undercut slots formed in the outer faces thereof, said rails having a central undercut slot in each of the adjacent faces, side plates carried by 65 some of said flanges, enlarged continuous beads formed along said side plates adjacent to one edge thereof, said enlarged beads engaging in some of the portions of said undercut slots in the flanges of the spaced 70 rails, said side plates having the free edges thereof disposed to contact with the outer faces of the unused flanges of the opposite rail, said side plates being reversibly connected to said rails, said rails having central 75 undercut slots formed therein, central sealing bars reversibly carried by said rails in said undercut slots, having beads formed thereon to engage in said central undercut slot and said central sealing bars having 80 contacting faces formed thereon so that when said rails are disposed in parallel relation, the side plates carried by each member contact with portions of the other rail to form a series of contacting sealing faces 85 between the separable parts of the composite bar.

In testimony whereof I affix my signature in presence of two witnesses.

CLARENCE A. FULLERTON.
